UNITED STATES PATENT OFFICE

JARED A. AYRES, OF MYSTIC RIVER, CONNECTICUT, ASSIGNOR TO THE PNEUMATIC ENGINE COMPANY, OF SAME PLACE.

BOILER-FEED APPARATUS FOR ENGINES.

SPECIFICATION forming part of Letters Patent No. 274,102, dated March 20, 1883.

Application filed December 7, 1881. (No model.)

To all whom it may concern:

Be it known that I, JARED A. AYRES, of Mystic River, in the county of New London and State of Connecticut, have invented certain new and useful Improvements in Boiler-Feed Apparatus for Engines, of which the following is a specification.

My invention relates primarily to apparatus for furnishing motive power for domestic purposes—such, for instance, as the ventilation of rooms or the driving of household machinery; and it consists in combining with a suspended boiler a water-supply tank or source, a pump for conveying water from said source to the boiler, and mechanism actuated by the rise and fall of said boiler to govern the effective action of said pump; in combining with a suspended boiler an engine to which it supplies steam, a water-supply pump driven by said engine, and mechanism actuated by the rise and fall of said boiler to permit or prevent the flow of water thereto through the agency of the pump; in combining with a suspended boiler an engine to which it supplies steam, an air-compressing pump driven continuously thereby, an air duct or pipe leading from said pump to a closed water-box, a water-supply pipe leading from the box to the boiler, a blow-off hole in the air-pipe, and a valve operated by the rise and fall of the boiler to close or open said blow-off hole; in providing a steam-engine and a pumping or air-forcing engine to act in connection with the boiler and water-supplying apparatus arranged as indicated, the whole constituting a self-regulating apparatus for supplying the desired power, and in various details and combinations hereinafter more fully set forth.

The object of my invention being to furnish a cheap and reliable power for domestic uses—as, for instance, driving sewing-machines, operating churning and washing-machines, ventilating, and similar purposes—its primary feature is the peculiar arrangement of a steam-engine and air forcing or pumping engine, whereby air may be compressed and carried through pipes to the various places at which it is desired to apply the power and the operation of the apparatus rendered automatic.

The various details hereinafter described are

arranged with a view to this end, but are susceptible of separate application in some cases.

In the accompanying drawings, Figure 1 represents a top plan view of an apparatus constructed in accordance with my improvements; Fig. 2, a vertical central section of said apparatus, showing the boiler or steam-generator sustained in accordance with my improved plan above an ordinary heating grate or stove; Fig. 3, a vertical central section at right angles to the foregoing through the apparatus, including the water-supply box and the hot-well, in which the latter is or may be sunk; Figs. 4 and 5, side and front views, partly in section, of a modified form of the apparatus.

A represents a boiler or steam-generator, which may be of any well-known construction, with or without flues or tubes, and which is placed within a cylinder, B, of sheet-iron or other suitable material. This boiler or generator is suspended by a link, yoke, or stay-rod, C, from the short arm of a lever, D, the long arm of which is graduated and carries a sliding weight, E, which may be adjusted to any point upon the arm to elevate the boiler when the water therein falls below a certain level. A stop or support is or may be provided to receive the lever when in its depressed condition. The lever D is mounted upon a horizontal shaft or pivot, F, carried in standards or brackets G, secured upon the cap-plate or top of the drum or cylinder, or extending up on opposite sides of said drum from the ground or base upon which the apparatus stands. When the standards are secured upon the cap-plate, as shown in Fig. 1, the latter will of course remain stationary as the boiler is raised and lowered, the link or yoke C in such case passing through openings therein, but when the standards extend from the ground or base, as in Fig. 5, the boiler may be suspended from the cap-plate or top, and the latter in turn suspended from the short arm of the lever, and arranged to rise and fall therewith, its rise admitting air above the fire and deadening the same.

Upon the cap-plate of the cylinder or drum B is mounted a steam-engine, H, preferably oscillating, as shown. The piston-rod of this engine drives a shaft, I, provided with a suit-

able balance-wheel, which shaft in turn drives an air-pump, J, for compressing air to afford a source of energy for the purposes mentioned, and also a secondary small air-pump or boiler 5 feed-pump, K, which latter is connected by an air duct or pipe, a, with the top of a water-box, L, standing in a tank or well, M, or otherwise having access to a body of water. Preferably, however, the tank is used, and the waste or 10 exhaust steam turned into it by a suitable pipe, b, so that its contents may be kept at a comparatively high temperature.

From near the bottom of the water-box a pipe, c, leads to the boiler, passing down beneath the water surface therein, and being provided with a flexible connection or telescopic joint to compensate for its rise and fall. In the bottom of said box also is an ordinary induction-valve, d, by which communication is 15 had with the surrounding body of hot water. In the air duct or pipe is a small hole, e, a blow-off hole, closed by a rubber valve, f, carried by a short lever, N, pivoted to the cap-plate, and crossing the pipe or an offset therefrom immediately above said hole. At its free end this lever, hereinafter called the "valve-lever," is provided with a yoke, g, which loosely encircles the free arm of the boiler supporting or sustaining lever. A spring, h, is so applied 20 as to tend constantly to force the valve-lever toward the blow-off hole to keep the latter closed.

When fire is made the engine, air-pump, and boiler feed-pump run continuously. So long as 35 the boiler is insufficiently supplied with water the valve will be depressed, the blow-off closed, and the pressure of the air, supplied through pipe a by the feed-pump, will force a constant stream from the water-box into the boiler. As 40 soon as the latter is properly filled it sinks slightly, its range of movement being in fact very limited, and raises the free end of its supporting-lever, thereby throwing up the valve-lever and opening the blow-off hole. When 45 the air blows off from the pipe and water-box the flow to the boiler ceases, the induction-valve in the bottom of the box opens, and it refills. As the water in the boiler evaporates it will again rise, the valve-lever will close, 50 and the flow recommence.

In the modification shown in Fig. 4 the small air-pump is dispensed with and the boiler is furnished with two tubes or pipes, a' and b', passing through its top and terminating one 55 just below the top and the other near the bottom thereof, said tubes communicating in a corresponding manner with the upper and lower sides of a water-reservoir, L', and being either jointed or of such length as to permit 60 them to rise and fall with the boiler without impairing their connection with the reservoir. The tubes or pipes a' b' are each provided with a valve, c', connected by a link or rod, d', to an arm, e', fast upon the rock-shaft or pivot 65 F, which, in this instance, is keyed to the lever in such manner that as the boiler rises and

the weight falls the valves are opened, while by the falling of the boiler the action is reversed and the valves are closed. The reservoir L' communicates, by means of a supply-70 pipe, f', containing a check-valve, with a water tank or supply located at any convenient point. Under this last construction and arrangement it will be seen if water be supplied to the boiler in proper quantity and heated to 75 produce steam the latter will be supplied until the water in the boiler falls so low as to permit the weight to overbalance the boiler, whereupon the boiler will rise, and in doing so will open the valves c', permitting steam to 80 escape through the pipe a' into the reservoir L'. The condensation of the steam within the reservoir, producing a vacuum therein, will cause water to ascend through supply-pipe f' into said reservoir, from which it may subsequently flow into the boiler. After the reservoir has been thus supplied the future action of replenishing it with water and of feeding the boiler becomes entirely automatic and regular, the boiler rising as the water-supply 85 therein falls to a certain level and the valves c' being thereby opened, allowing steam to pass from the top of the boiler to the top of the reservoir, and water to pass from the bottom of the reservoir to the bottom of the boiler 90 until the latter receives its proper supply, when it again falls, closing the valves and allowing the steam within the reservoir to condense and raise water through the pipe f', thus maintaining at all times a uniform quantity of water in the boiler and avoiding the dangers attending a lack of water therein. 95

When the cap-plate or top of the drum or cylinder B is fixed and only the boiler arranged to move, the steam-pipe may be made to telescope or slide one part upon another to compensate for the movements of the boiler. 105

It is desirable that the heat be partially cut off or reduced during the supplying of the boiler, and to this end I establish a connection, 110 by means of a rod or chain, g', between the lever by which the boiler is carried and the damper or draft, in case a stove is used, or the wick-regulator or gas cock or valve, in case a lamp or gas be employed for heating the boiler, 115 the arrangement being such that as the boiler rises the draft shall be cut off or the flame reduced, but that as it descends they shall be again restored to their former condition. In Fig. 1 an ordinary stove is represented and its 120 lower door or draft-regulator, I', is shown as connected with the lever, while in Fig. 4 a lamp-heater is represented, the wick-wheel J' of which is connected with the lever D and controlled by its movements. 125

It is also desirable that steam shall not form more rapidly than it is required for use, and hence a second regulator for controlling the draft or the flame is provided, depending for its action upon the steam-pressure in the boiler. 130 In Fig. 2 the arrangement is shown applied to a damper or draft-regulator, K', which is inde-

pendent entirely of the door I, and is arranged to move vertically across the air-inlet, being connected by a rod or chain to the top plate of an expansible chamber or body, P, into which 5 steam is admitted by a pipe or tube from the boiler. The top plate of the expansible chamber may be weighted to regulate the degree of pressure at which it may rise; or the inlet may be regulated to control the admission of steam 10 thereto.

The air compressed by the main air-forcing pump, operated by the steam-engine, is forced through tubes or pipes to the various rooms or points at which it is desired to apply power, 15 and at these points air-engines are located and driven by the air thus supplied.

In applying the compressed air to the driving of sewing-machines and other mechanism which it is desirable or necessary to move about 20 the room, it is preferred to connect with the main supply-pipe by flexible tubing, which may be carried in any desired direction.

This apparatus is peculiarly adapted to churning, as there is an entire absence of heat 25 and odor at the point at which the work is performed, air instead of steam being used to operate the engine or motor mounted upon or by the side of the churn. In view of the readiness with which milk and its products take 30 up odors and are affected by heat, the importance of this difference will be at once seen.

The usual steam-gage, safety-valve, and other fittings will or may be employed.

I do not claim herein, broadly, the employment of the blow-off tap between the continuously-driven air-forcing pump and the closed water-box to intermit or insure the supply of water to the boiler; nor do I claim the combination, with the closed water-box and pumping 35 mechanism, of the hot-water tank receiving the exhaust-steam from the engine, such being the subject-matter of an application filed by me on the 15th day of June, 1882. Neither do I claim broadly herein the combination with 40 the blow-off vent of the valve automatically controlled by the fluctuations of water in the boiler, having made this the subject-matter of another application filed by me on the 21st day of said month; but

50. What I do claim is—

1. In combination with a suspended boiler, a water-supply tank or source, a pump for forcing or conveying water from said source to the boiler, and mechanism actuated by the 55 rise and fall of the boiler to govern the effective action of the pump.

2. In combination with a suspended boiler, an engine to which it supplies steam, a water-supply pump driven by said engine, and mechanism 60 actuated by the rise and fall of the boiler to permit or prevent the flow of water thereto through the agency of the pump.

3. In combination with a suspended boiler,

an engine to which it supplies steam, an air-compressing pump driven continuously thereby, 65 an air duct or pipe leading from said pump to a closed water-box, a water-supply pipe leading from the box to the boiler, a blow-off hole in the air-pipe, and a valve operated by the rise and fall of the boiler to close or open 70 said blow-off hole.

4. In combination with a boiler suspended from a weighted lever, an engine to which said boiler supplies steam, an air-compressing pump driven continuously by the engine, an air duct or pipe leading from said pump to a closed water-box, a hot-well in which said water-box is suspended and from which it is supplied, a supply-pipe leading from the water-box to the boiler, a blow-off hole in the air-pipe, and a valve controlled by the rise and fall of the boiler to close or open 80 said hole.

5. In combination with a boiler suspended from a weighted lever, an engine to which said boiler supplies steam, an air-compressing pump driven continuously by the engine, an air duct or pipe leading from said pump to a closed water-box, a hot-well in which said water-box is suspended, a valve communicating between the water-box and the well to admit water 85 from the latter to the former, a supply-pipe leading from the box to the boiler, a blow-off hole in the air-pipe, and a valve-lever closing said blow-off hole and connected with the boiler-supporting lever, so as to be operated 90 by its movement.

6. An organized apparatus for supplying power for domestic use, consisting of a balanced steam-boiler, a boiler-feed controlled by the rise and fall of said boiler, a steam-engine arranged to receive steam from the boiler, and a pump or air-forcing apparatus connected with and operated by the steam engine to supply 100 power to distant motors.

7. In combination with the suspended boiler, 105 the oscillating steam-engine fed thereby, the main air-forcing pump driven by said engine, the secondary air-pump or boiler feed-pump, also driven by the engine, the air-pipe, water-box, and water-supply pipe, and mechanism, 110 substantially such as described, controlled by the rise and fall of the boiler to render effective or ineffective the action of the secondary air-pump.

8. In combination with a steam-boiler adapted to rise and fall in accordance with the quantity of water therein, a heating-chamber having a cap-plate or top arranged to rise and fall in unison therewith and to admit or exclude air above the fire, as and for the purpose 120 set forth.
